UNITED STATES PATENT OFFICE.

ELMER A. SPERRY, OF BROOKLYN, NEW YORK, ASSIGNEE TO SPERRY DEVELOPMENT COMPANY, OF DOVER GREEN, DELAWARE, A CORPORATION OF DELAWARE.

COOLING MEANS FOR INTERNAL-COMBUSTION ENGINES.

Application filed July 20, 1921. Serial No. 486,182.

This invention relates to the cooling of internal combustion engines, particularly those of the Diesel type, wherein combustion is obtained by injecting the combustible fuel at the proper time into compressed air. Heretofore it has been the practice to employ the same fluid medium, usually water, to cool both the combustion chambers and the cylinders of such engines as is customary in internal combustion engines generally. The temperature at which the cylinders should be kept, however, for permitting proper lubrication, is much lower than the temperature which may be permitted in the combustion chambers of engines of the Diesel type. Furthermore, the higher the temperature of the combustion chamber, the more complete and rapid will be the combustion of the explosive fuel. Accordingly, the chief object of my invention is the provision of means for maintaining the combustion chambers at a temperature considerably higher than that which is proper for the engine cylinders while at the same time maintaining said cylinders at temperatures suitable for permitting proper lubrication. For this purpose I cool the combustion chambers by means of a fluid having a lower specific heat than the fluid used to cool the engine cylinders. At present I prefer to cool the combustion chambers by some liquid such as kerosene (which has a specific heat of .5) although it will be evident that the invention is not confined to any specific liquid. The walls of the cylinders may be cooled by water and, if desired, water may also be utilized for preventing overheating of the liquid employed to maintain the combustion chambers at the proper temperature.

Referring to the drawings wherein I have shown what I now consider to be the preferred form of my invention:

Fig. 1 is a vertical sectional view of a portion of a multiple expansion Diesel engine showing my invention applied thereto.

Fig. 2 is a plan view of the parts shown in Fig. 1, the surrounding water jacket being shown in section.

Fig. 3 is a vertical sectional view taken

Fig. 4 is a horizontal sectional view taken on line 4—4 of Fig. 1.

I have shown my invention in connection with a multiple expansion Diesel engine, although it will be apparent that the application of the invention is not restricted to engines of the multiple expansion type. The engine in connection with which I have illustrated my invention is of the general type shown for example in my Patent No. 1,325,810, granted December 23, 1919, for "multiple expansion internal combustion engines". Since this type of engine is well known in the art I have shown only one of the high pressure cylinders 1 and a portion of the low pressure cylinder 2. The combustion chamber of the cylinder 1 is shown at 3 above said cylinder and extending over a portion of the low pressure cylinder. A valve for admitting combustible fuel into the chamber 3 is shown at 4 while 5 denotes a combined intake and transfer valve for admitting compressed air into the combustion chamber and controlling the transfer of gases from the high pressure cylinder to the low pressure cylinder. The specific forms of these valves form no part of my invention and will hence not be described here. The usual piston 6 is shown in the high pressure cylinder, while the low-pressure piston is shown at 7.

Surrounding the top and sides of the combustion chamber is a jacket or chamber 8 for the reception of kerosene or other cooling medium of substantially less specific heat than the liquid employed to cool the walls of cylinder 1. The said jacket or chamber 8 may open directly into or otherwise communicate with a passage 9 which extends around said combustion chamber slightly below the latter. In fact, passage 9 may be said to form the lower part of chamber 8. Communicating with said passage 9 through a suitable opening 10 is a pipe or conduit 11 which extends, as shown, on opposite sides of said opening. Inclined pipes 12 connect one portion of conduit 11 with a conduit 13 located above the combustion chamber, while another series of inclined pipes 12' provides communication

between the opposite portion of conduit 11 and a conduit 13' positioned on a level with conduit 13. The conduits 13 and 13', as shown clearly in Figs. 2 and 3, communicate with the upper portion of chamber 8. Communicating through an opening 14' with the portion of passage 9 opposite opening 10 is a conduit 14 similar to conduit 11. Inclined pipes 15 connect conduit 13 with one portion of conduit 14, and similarly, inclined pipes 15' serve to connect the opposite portion of conduit 14 with conduit 13'.

From the structure above described it will be apparent that effective provision is made for the circulation of cooling fluid about the combustion chamber. It will be seen that when the desired cooling liquid is placed in the aforesaid conduits, pipes, and cooling chamber 8 and the liquid in chamber 8 and passage 9 becomes heated by the combustion of the explosive fuel, such liquid rises and flows over the top and sides of the combustion chamber, as indicated by the arrows in Fig. 4. The heated liquid thus flows from all points on passage 9 up over the sides and top of the combustion chamber to conduits 13 and 13'. As the heated liquid rises towards the last named conduits cooler liquid flows from said conduits and the inclined pipes into passage 9 and chamber 8 to take the place of the heated liquid. As the latter liquid passes into conduits 13 and 13' and thence down the inclined pipe 12, 12', 15 and 15', said liquid is cooled and is ready upon reaching conduits 11 and 14 to again extract heat from the combustion chamber. Thus a circulation of liquid about the top and sides of the combustion chamber is maintained, the liquid extracting heat from the combustion chamber and in turn being cooled between the time when it flows out of contact with said chamber and the time when it returns into contact therewith.

To aid in the cooling of said liquid the said conduits, inclined pipes, and chamber 8 may be surrounded by a water jacket 16. This jacket may form an extension of the water jacket 17 which surrounds the major portion of the high pressure cylinder 1. By this means the temperature of the combustion chamber cooling liquid may be kept from rising too high and said liquid may further be effectively cooled during its passage along the inclined pipes connecting conduits 13 and 13' with conduits 11 and 14. The water may be circulated in any suitable manner, a suitable exit therefor being shown at 20. The combustion chamber cooling liquid, having substantially less specific heat than the water which cools the high pressure cylinder, permits the temperature of said combustion chamber to rise considerably higher than would be the case if water were employed as the cooling medium for the com-

bustion chamber, and thus aids the rapidity 65 and completeness of the combustion of the explosive mixture. At the same time the temperature of said combustion chamber is prevented from rising above a predetermined amount beyond which it would be undesirable for the temperature to rise. The water surrounding cylinder 1 maintains the 70 temperature of the latter sufficiently low to permit proper lubrication.

It should be noted that I have shown the 75 water-cooled portion of the cylinder 1 terminating short of the top portion of the cylinder and have further shown the passage 9 extending along a part of said top portion. The cooler portions of the walls of said cylinder are thus separated from the combustion chamber and the rate of cooling of the latter may thus be diminished. As shown 80 in Fig. 2, the passage 9 is substantially elliptical in shape, since it follows the contour of the combustion chamber, and extends along only a portion of the top part of cylinder 1. If desired, a branch passage 18 may be provided on a level with passage 9 extending along that part of the top portion of cylinder 90 1 that is not cooled by the liquid in passage 9. Passage 18 extends across the passage 9 and communicates at each of its ends with said passage, so that some of the combustion chamber cooling liquid may flow through 95 said passage 18. A flow of said liquid about the entire top portion of cylinder 1 may thus be provided.

The combined transfer and intake valve 5 may be water cooled and for this purpose 100 I have shown a water jacket 21 surrounding said valve. This jacket may be an extension of the water jacket 16. It should be further noted that the liquid utilized to cool the combustion chamber may be employed 105 to cool the low pressure cylinder 2 or any desired portion thereof.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by 110 other means. Also, while it is designed to use the various features and elements in the combination and relations described, some of these may be altered and others omitted 115 without interfering with the more general 120 results outlined, and the invention extends to such use.

Having described my invention what I claim and desire to secure by Letters Patent 125 is:

1. In combination with a cylinder and a combustion chamber of an internal combustion engine, fluid means for cooling said cyl-

inder and fluid means of lower specific heat and lower heat conductivity for cooling said combustion chamber.

2. The method of cooling a cylinder and a combustion chamber of an internal combustion engine which comprises extracting heat from said cylinder by a fluid and extracting heat from said combustion chamber by a fluid of less specific heat and lower heat conductivity than the first mentioned fluid.

3. In combination with a cylinder and a combustion chamber of an internal combustion engine, means for extracting heat from said combustion chamber and means for extracting heat from said cylinder at a greater rate than from said combustion chamber.

4. In combination with a cylinder and a combustion chamber of an internal combustion engine, a liquid in contact with said cylinder and a liquid of less specific heat and lower heat conductivity than the first mentioned liquid in contact with said combustion chamber.

5. In combination with a cylinder and a combustion chamber of an internal combustion engine, means for cooling said cylinder by a given liquid, and means for cooling said combustion chamber by a different liquid of lower specific heat and lower heat conductivity.

6. In combination with a cylinder and a combustion chamber of an internal combustion engine, fluid means for cooling said combustion chamber, and fluid means of different specific heat for cooling said cylinder and the first mentioned fluid means.

7. In combination with a cylinder and a combustion chamber of an internal combustion engine, a liquid in contact with said combustion chamber, and a different liquid in contact with said cylinder and in heat conductive relation to said first mentioned liquid.

8. The method of cooling a cylinder and a combustion chamber of an internal combustion engine which comprises extracting heat from said combustion chamber by a liquid and extracting heat from said cylinder and said liquid by another liquid.

9. In combination with a cylinder and a combustion chamber of an internal combustion engine, means for cooling said combustion chamber by a given liquid, and means for cooling said liquid and said cylinder by another liquid.

10. In combination with a cylinder and a combustion chamber of an internal combustion engine, a chamber for maintaining a cooling liquid in contact with said cylinder, and a chamber for maintaining a cooling liquid of lower specific heat and lower heat conductivity in contact with said combustion chamber.

11. In combination with a cylinder and a combustion chamber of an internal combus-

tion engine, a chamber for maintaining a cooling liquid in contact with the top and sides of said combustion chamber, a conduit communicating with the lower portion of said second mentioned chamber, a conduit communicating with the upper portion of said second mentioned chamber, and a plurality of pipes connecting said conduits.

12. In combination with a cylinder and a combustion chamber of an internal combustion engine, a chamber for maintaining a cooling liquid in contact with the top and sides of said combustion chamber, conduits communicating with opposite parts of the lower portion of said second mentioned chamber, conduits communicating with the upper portion of said second mentioned chamber, inclined pipes connecting one of the second mentioned conduits with the first mentioned conduits, and other inclined pipes connecting the other of the second mentioned conduits with said first mentioned conduits.

13. In combination with a cylinder and a combustion chamber of an internal combustion engine, a chamber for maintaining a liquid in contact with the top of said combustion chamber, and a chamber for maintaining a liquid of higher specific heat and higher heat conductivity in contact with portions of said cylinder spaced from said combustion chamber.

14. In combination with a cylinder of an internal combustion engine, a combustion chamber communicating with the upper portion of said cylinder, means for maintaining a fluid in contact with said combustion chamber and with a portion of said cylinder adjacent said combustion chamber, and means for maintaining a fluid of higher specific heat and higher heat conductivity in contact with another portion of said cylinder.

15. In combination with a cylinder of an internal combustion engine, a combustion chamber communicating with the upper portion of said cylinder, means for maintaining a liquid in contact with said combustion chamber and with a portion of said cylinder adjacent said combustion chamber, and means for maintaining a different liquid in contact with another portion of said cylinder and with said first named means.

16. The method of cooling a cylinder and a combustion chamber of an internal combustion engine which comprises maintaining a liquid in contact with said chamber and with a portion of said cylinder adjacent said chamber, and maintaining a liquid of higher specific heat and higher heat conductivity in contact with another portion of said cylinder.

17. The method of cooling a cylinder and a combustion chamber of an internal combustion engine which comprises maintaining a liquid in contact with said chamber and with a portion of said cylinder adjacent said

chamber, and extracting heat from said liquid and another portion of said chamber by a different liquid.

18. In combination with a cylinder of an internal combustion engine, a combustion chamber communicating with the upper portion of said cylinder, a chamber for maintaining a liquid in contact with said combustion chamber, said second mentioned

chamber extending downwardly below said combustion chamber and surrounding a portion of said cylinder, and means for maintaining a liquid of higher specific heat and higher heat conductivity in contact with another portion of said cylinder. 15

In testimony whereof I have affixed my signature.

ELMER A. SPERRY.
